UNITED STATES PATENT OFFICE.

JOHN G. BLESSING, OF CHICAGO, ILLINOIS, ASSIGNOR TO AUTOMATIC ELECTRIC COMPANY, OF CHICAGO, ILLINOIS, A CORPORATION OF ILLINOIS.

CALLING DEVICE FOR AUTOMATIC TELEPHONE SYSTEMS.

1,317,152.

Specification of Letters Patent. Patented Sept. 30, 1919.

Application filed November 22, 1916. Serial No. 132,740.

To all whom it may concern:

Be it known that I, JOHN G. BLESSING, a citizen of the United States of America, and a resident of Chicago, county of Cook, and 5 State of Illinois, have invented certain new and useful Improvements in Calling Devices for Automatic Telephone Systems of which the following is a specification.

My invention relates in general to calling 10 devices, or impulse senders as they are sometimes termed, for use at the substations in an automatic telephone system, and the principal object of the invention is to combine a calling device and a desk telephone 15 in one instrument in order to form a more compact and efficient substation set than has hitherto been available.

The foregoing and other useful objects are attained in a manner and through means 20 which will be fully described and explained hereinafter reference being had to the accompanying drawings.

In the drawings, Figure 1 is a vertical cross section of a desk type telephone embodying the principles of my invention, Fig. 25 Fig. 2 is a horizontal cross section taken on the line Z, Fig. 3 shows a mounting plate contained in the base and carrying the impulse sending mechanism proper, Figs. 4 and 5 show details of the said mechanism, Fig. 6 30 is a front view in perspective showing the sliding finger hole dial, Fig. 7 is a detail showing of the dial locking device, and Fig. 8 is a circuit diagram.

35 Referring now particularly to Figs. 1, 2, and 7, the base 2 is preferably a metal stamping of the form shown in Fig. 1. A heavy metal ring 9, which is turned down to a smaller diameter at its upper end, has its 40 lower end fitted inside the base and secured thereto by brazing. The upright frame is made of a tube 8 which is fitted over the upper end of the ring 9 and which is also brazed or soldered to the ring. The tube 45 8 is cut away in front and in back leaving only two upright portions 13 and 14, seen clearly in Fig. 7, which support at the top a transmitter head 5. A plate 15 extends from the ring 9 to the transmitter head 5 and 50 is in line with the front edges of the uprights 13 and 14, to which it may be soldered or brazed, and which, in addition to strengthening the frame, affords a means for mounting the receiver hook and also serves as a

runway for the slidable finger hole dial, as 55 will appear more clearly hereinafter.

The slidable setting member, herein for convenience termed a dial, comprises a curved segment 17, which is cut from a tube of slightly smaller diameter than the tube 8, 60 and which is secured to two metal blocks 18 and 19. The back plate 20 is secured to the blocks 18 and 19 by short screws two of which may be seen in Fig. 1. A glass plate 21 is clamped between the blocks 18 and 19 65 and the back plate 20 and has affixed to its rear surface a card bearing the usual series of digits from 1 to 0. The dial as a whole is adapted to slide up and down between two flanges 6 and 16 on the plate 15, a segment 70 of the ring 9 being cut away at 11 to permit the lower end of the dial to pass through. The dial is held in place by the outer tube 4 which fits closely over that portion of the tube 8 which has not been cut away and 75 which has an opening in front of the dial, as is best seen in Fig. 6. The outer casing is completed by the cap 24 which fits down over the transmitter head 5 and the tube 4.

The receiver hook passes through a slot 80 in the cap 24 and is pivoted to the plate 15 by means of a screw 32. Just inside the cap 24 the hook rests on a lug 33 attached to a vertically slidable rod 34 by means of which the contact springs 36, 37, and 38 are controlled. The lower end of the rod 34 is turned down as at 39 and passes through a hole in the ring 9. When the receiver is removed the hook is raised under the influence of a spring 35 which is compressed between 90 the larger diameter of the rod 34 and the ring 9.

Referring now more particularly to Figs. 3, 4, and 5, the base plate 3 may be mounted within the base 2 in any suitable manner, 95 being, however, preferably secured to the ring 9 by means of two screws 40 and 41. The semicircular fiber ring 44 carries the terminals 45 which afford a means for connecting the conductors of the usual flexible 100 cord with the instrument wiring. Also mounted on the plate 3 are the impulse springs 42 and 43 and the hook springs 36, 37 and 38. The mechanism for controlling the impulse springs 42 and 43 comprises a 105 shaft 48 which is clamped between the members 46 and 47 and secured to the plate 3 by means of screws 54 and 55. The shaft 48

carries a drum wheel 49 which has a hub 50 upon which is mounted a loose ratchet wheel 51. The fiber impulse wheel is rigidly secured to the ratchet 51. Motion is transmitted from the drum wheel 49 to the impulse wheel 52 by means of a pawl 54 which is adapted to engage the teeth in the ratchet 51. The relation of these parts may be readily understood from Fig. 5. The drum wheel 49 is hollow and contains a clock spring 53 which is fastened at one end to the shaft 48 and at the other end to the wheel 49.

The impulse sending mechanism which has just been described is controlled or set by the sliding dial through connecting devices which will now be described. In Fig. 1 is seen a cylinder 56 which passes through the hole in ring 9 and is suitably secured to the said ring. Between the cylinder 56 and the plate 15 there is slidably mounted a member 27 which has at its upper end a right angle bend 30 secured to the hub 26, and at its lower end a tongue 29 which projects through a slot 7 in the plate 15 and supports the finger hole dial. Lateral movement of the member 27 above is prevented by the crosspiece 57, shown in Fig. 7. A slot 12 is cut in ring 9 to permit the passage of the tongue 29. Motion is communicated from the sliding member 27 to the drum wheel 49 of the impulse sending mechanism by means of a steel ribbon 28 which is secured at one end to the said drum wheel, around which it is wound several times, and is then passed up through a slot 10 in the ring 9 and over a pulley 31, and is then riveted to an extension of the hub 26. The clock spring 53 is tightened by first loosening the screws 54 and 55 slightly, after which the shaft 48 may be turned to tension the spring. The limit of the upward movement of the sliding member 27 is determined by the engagement of the tongue 29 with the upper end of the slot 7. A retarding device for regulating the speed at which the dial returns to normal comprises the cylinder 56 and a piston rod 25 which is screwed into the hub 26. A tapered screw 60 regulates the admission of air into the lower end of the cylinder.

When the receiver is hung up the sliding member 27 is locked against downward movement by means of a lever 61 which is pivoted at 52 on the opposite side of the plate 15 from the receiver hook. See Fig. 7. The hook being down the horizontal end of lever 61 is forced down by spring 62 until the notch in the lower end of the said lever engages a projection 63 on the crosspiece 57.

It is understood, of course, that the usual transmitter, receiver, and ringer are provided, and these parts have been indicated in the circuit drawing Fig. 8.

Having described briefly the construction

and mechanical relation of the various parts of my improved calling device, I will now proceed to explain the manner in which the same is operated.

The function of a device of this character, as is well known, is to produce series of breaks or interruptions in the substation line circuit corresponding to the different digits in a called number. Bearing this fact in mind and with occasional references to the circuit diagram of Fig. 8, the explanation of the operation may be proceeded with.

When the receiver is on the hook, which is the normal condition, the contact springs 37 and 38 are in engagement, whereby the ringer K is connected in bridge of the line conductors 70 and 71, as seen in Fig. 8. When in this condition the substation is ready to receive calls.

When the receiver is removed to initiate a call, the rod 34 is raised by the spring 35, whereby the contact springs 37 and 38 are separated and the former spring is brought into engagement with contact spring 36. As the result of the shifting of these contact springs the ringer K is disconnected and the serially connected receiver R and transmitter T are bridged across the line conductors in the usual manner. In addition to shifting the switching springs, the rod 34, by means of the lug 33, disengages the lever 61 of the dial locking device from the projection 63. The removal of the receiver, then, places the circuits at the substation in condition for talking and unlocks the dial. At the exchange, in the more generally used systems, the removal of the receiver at one of the substations is followed by the automatic operation of preliminary trunking apparatus whereby the calling line is extended to an idle selector switch.

The calling subscriber will now proceed to manipulate his calling device in accordance with the first digit of the desired number, which will be assumed to be the digit 5. The operation is as follows: The finger is placed in the finger hole of the dial corresponding to the digit 5 and the dial is pulled down until the finger strikes the stop 80, after which the finger is withdrawn to permit the dial to return to normal. When the dial is pulled down it carries with it the sliding member 27, which in turn, operates to, unwind the steel ribbon 28 from the drum wheel 49, thereby turning the latter to tension the clock spring 53. Additionally the piston 25 is forced down in the cylinder 56 and some of the air in the cylinder is forced out past the tapered screw 60. The drum wheel 49 is of such diameter that when the dial is pulled for the digit 5 the said wheel will be rotated by the unwinding of the ribbon 28 a sufficient distance to cause the pawl 54 to pass five teeth on the ratchet wheel 51. Now

when the dial is released by the finger of the operator, the drum wheel 49 is returned to normal by the clock spring 53, thereby winding up the ribbon 28 and raising the dial until the tongue 29 reaches the top of the slot 7. As the drum wheel returns to normal the pawl 54 engages the last tooth of the ratchet wheel past which it was rotated whence it follows that the return movement of the drum wheel is accompanied by the rotation of the ratchet wheel. Since the teeth on the impulse wheel 52 are spaced the same as the teeth on the ratchet wheel 51 it will be obvious now that on the return of the drum wheel to normal the impulse wheel will separate the impulse springs 42 and 43 five times to cause five breaks or interruptions in the line circuit. The speed at which the impulses are transmitted may be varied by adjusting the tapered screw 60 which regulates the admission of air to the cylinder 56.

The selector switch at the exchange having operated responsive to the interruptions just produced in the line circuit, the calling subscriber may now proceed to manipulate his calling device in accordance with succeeding digits of the desired number whereby additional series of interruptions are produced in the line to cause the successive operations of other automatic switches to complete the required connection. It is understood that each time a digit is pulled on the dial, the pawl on the drum wheel is rotated past a corresponding number of teeth on the ratchet wheel, so that the number of impulses transmitted will in every case correspond to the digit called.

It will be seen from the foregoing that I have made radical changes and improvements in calling devices of the general character described, whereby a calling device and a desk telephone are combined to form an exceedingly compact and efficient substation telephone set. Departures may be made from the exact structure disclosed, and I do not, therefore, wish to limit myself to the precise form shown in the drawings, but desire rather to include and have protected by Letters Patent all modifications of my invention which may hereafter be devised, limited only by the scope of the appended claims.

What I claim as my invention is:

55 1. In a substation telephone set, the combination with a rotary impulse sender, of a longitudinally movable setting member, and connecting means whereby said sender may be variably controlled through the medium of said setting member.

2. In a substation telephone set, the combination with a rotary impulse sender, of a single setting member movable only in a straight line for variably controlling said impulse sender, and means for translating

the linear movement of said setting member into a rotary movement of the said sender.

3. In a substation telephone set, a line circuit, a rotary device for interrupting said circuit, and means for controlling said device comprising a longitudinally movable finger hole dial. 70

4. In a substation telephone set, a line circuit, a spring controlled wheel, a single longitudinally movable setting member 75 adapted when operated to rotate said wheel from its normal position against the tension of its controlling spring, and an impulse sending device variably actuated by said wheel on its return to normal to produce 80 interruptions in the said line circuit.

5. In a substation telephone set, the combination with a desk telephone having an upright tubular casing, of a rotary impulse sender, and a setting member for said 85 sender slidably mounted inside said casing.

6. In a substation telephone set, the combination with a desk telephone having an upright tubular casing, of a rotary impulse sender, and a setting member for said sender 90 mounted inside said casing and having a series of finger holds disposed on a line parallel thereto.

7. In a substation telephone set, the combination with a desk telephone having an 95 upright tubular casing, of a rotary impulse sender, and a setting member for said sender movable on a line parallel to the said casing.

8. In a substation telephone set, the combination with a desk telephone having an 100 upright tubular casing, of a rotary impulse sender, a manually operable controlling member for said sender disposed within the said casing, an opening in the casing in front of the said member, and finger holds in the 105 said member accessible through said opening.

9. In a substation telephone set, the combination with a desk telephone having a base and an upright frame, of an impulse 110 sender in the base of said telephone, and a setting member for said sender slidably mounted on said frame.

10. In a substation telephone set, the combination with a desk telephone having a base and an upright frame, of an impulse 115 sender in the base of said telephone, a setting member for said sender slidably mounted on said frame, and means for communicating the movement of said setting member to the said sender. 120

11. In a substation telephone set, the combination with a desk telephone having a base and an upright frame, of an impulse sender in the base of said telephone, a sliding setting member mounted on said frame, and means for controlling said sender through the medium of said setting member. 125

12. In a substation telephone set, the combination with a desk telephone having a base and an upright frame, of an impulse sender 130

in the base of said telephone, a manually operable setting member slidably mounted on said frame, and mechanical connecting means between the said setting member and the said sender.

13. In a substation telephone set, the combination with a rotary impulse sender, of a setting member for said sender mounted independent thereof, and flexible connecting means whereby the said sender may be controlled through the medium of said setting member.

14. In a substation telephone set, the combination with a line circuit, of a rotary impulse sender for producing interruptions in said line, and an air controlled speed governor for said sender.

15. In a substation telephone set, the combination with a line circuit, of a rotary impulse sender for producing interruptions in said line, and a retarding device comprising an air cylinder and piston for regulating the rate at which said interruptions are produced.

16. In a substation telephone set, the combination with a rotary impulse sending device, of a manually operable controlling

member therefor movable only in a straight line, and locking means for said controlling member controlled by the receiver hook. 30

17. In a calling device, a rotary impulse sending mechanism, and a manually operable controlling member provided with finger holds arranged in a straight line.

18. In a substation telephone set, a desk telephone having a base and an upright tubular casing, an impulse sender within the said base, a rectangular opening in the said casing, and a controlling member for said sender disposed within the said casing behind the said opening.

19. In a substation telephone set, a desk telephone having a base and an upright tubular casing, an impulse sender within the said base, a rectangular opening in the said casing, a controlling member for said sender disposed within the said casing behind the said opening, and a plurality of finger holds in the said controlling member.

Signed by me at Chicago, Cook county, State of Illinois, this 14th day of November, 1916.

JOHN G. BLESSING.
